United States Patent

Des. 235,890
Patented July 15, 1975

235,890

CELL CULTURE VESSEL OR THE LIKE

Robert Dragotta, Vineland, N.J., assignor to
Bio-Research Glass, Inc.

Filed Nov. 4, 1974, Ser. No. 520,605

Term of patent 14 years

Int. Cl. 24—02

U.S. CL. D32—1

FIG.1

FIG.2

FIG.3

FIG. 1 is an elevational view of a cell culture vessel showing my new design;

FIG. 2 is a top plan view thereof; and

FIG. 3 is a bottom plan view thereof.

I claim:

The ornamental design for a cell culture vessel or the like, as shown.
